DOMESTIC DWELLING

Daniel Schwartzman, New York, N.Y., assignor to
Gordon E. Sugar, Pikesville, Md.

Filed Mar. 8, 1966, Ser. No. 1,356

Term of patent 14 years

(Cl. D13—1)

FIGURE 1 is a perspective view of a domestic dwelling embodying my new design;

FIGURE 2 is a top plan view;

FIGURE 3 is a front elevation;

FIGURE 4 is a rear elevation;

FIGURE 5 is an end elevation looking from the left in FIGURE 1; and

FIGURE 6 is an end elevation looking from the right of FIGURE 1.

The dominant features of my design reside in the portion shown in full lines, portions in FIGURES 2, 3, 4 and 6 being omitted for convenience of illustration only.

I claim:

The ornamental design for a domestic dwelling, substantially as shown and described.
